Vincent Raschella

UNITED STATES PATENT OFFICE.

VINCENT RASCHELLA, OF WEEHAWKEN, NEW JERSEY.

SHOE-POLISHING MACHINE.

1,329,677.

Specification of Letters Patent.

Patented Feb. 3, 1920.

Application filed March 7, 1918. Serial No. 221,044.

To all whom it may concern:

Be it known that I, VINCENT RASCHELLA, a citizen of the United States, residing at No. 12 Pleasant avenue, Weehawken, in the 5 county of Hudson and State of New Jersey, have invented a new and useful Shoe-Polishing Machine, of which the following is a specification.

My invention relates to a shoe-polishing machine in which two sets of revolving brushes operate in conjunction with a moving platform, and the object of my invention is: first, to afford facilities for a quick 10 shoe shine: second, to give to the shoe a per- 15 feet even gloss: and third, to enable any- body to get a good shine, without any use of hand work.

To attain the desired end, my invention consists in a certain novel, useful combination or arrangement of parts and peculiarities of construction, all of which will be 20 fully described and illustrated in the accompanying drawing, in which: Figure 1 is a vertical longitudinal sectional view of a 25 shoe polishing machine, embodying my invention. Fig. 2 is a plan view of the machine as seen from the top, the brush covers being broken away. Fig. 3 is an end elevation partly in section of the machine. Fig. 30 4 is a top plan view of the outer cup containing the polish. Fig. 5 is a sectional view of another cup which will fit into the previous one. Fig. 6 is a sectional view of the 35 cups of Figs. 4 and 5, assembled one into the other, forming an automatic device containing the polish. Fig. 7 is a fragmentary 40 view of a leather belt or moving platform, mounted on pulleys. Fig. 8 is a detailed view of part of the moving platform. Fig. 45 9 is a form of gaiter to be used as a protector of the hose for those who wear low shoes. Fig. 10 is an end view of a brush for the purpose of preliminary dusting of the shoes. Fig. 11 is a detail view of an adjustable curtain hanging from the cover of the machine.

Similar letters of reference, wherever occurring, indicate corresponding parts in all the figures.

50 In the drawings: A and B are two sets of revolving brushes, each set consisting of a plurality of brushes mounted on a shaft such as C or D. The shafts C and D are mounted in bearings S on supports at opposite sides of the belt E. E is a leather belt or moving platform, which carries the per-

son who is to have his shoes polished. F indicates a plurality of supporting rollers properly mounted in bearings on inclined supports G and immediately beneath the 60 leather belt or moving platform. Such rollers are revolved by the friction of the belt which moves on top of them when the machine is in action. The supports G are mounted on posts at each side of belt E. H 65 indicates stationary cleaning brushes. I and J are stationary platforms at the ends of the machine. K are blades mounted between the brushes to revolve with the same and the main shafts, for the purpose of 70 fanning and drying the shoes. L indicates automatic devices controlling the flow of polish from the cups, and are actuated by contact of lever T with the ankle when the shoe passes between the brushes. The inner 75 cup is rotatable within the outer cup and is rigidly secured to lever T. Said device is open when the openings h in the bottom of the inside cup register with the opening g in the bottom of the outside cup. Said cups 80 are held by the cover U, and they are interchangeable; that is, one set of cups contains black polish, while another contains tan, and they are to be used alternately when black and tan shoes are to be polished. M 85 indicates two controlling springs for turning the inner cup to closed position. N is a set of reducing gear sprocket chains and sprocket wheels to control the speed. O are hand railings for the person to take hold of 90 during the shining operation. P are short wire spikes suitably mounted on the leather belt, which constitutes the moving platform. U are covers to cover the brushes. Said 95 covers are hinged at V for the purpose of opening them when the brushes are to be changed. The dotted lines in Figs. 1, 2 and 3 show respectively the positions of the shoes being shined. W are adjustable curtains hanging from the cover U and adjustable by means of slot Y sliding up and down by a threaded button. Said curtains are to 100 protect the trousers of the customer from being soiled. Every set of brushes consists of a plurality of brushes fixed on their respective shaft. Each set revolves in the direction indicated by the arrow (Fig. 3). The revolving brushes are all of soft material except the stationary brushes H, which are of bristle.

105 The first brush of both sets, namely, a, b, is employed to dust off or clean the shoes at

the beginning of the shine. Then, as the platform slowly moves along and carries the person, his shoes approach the next set of brushes *c, d*, which are employed to put 5 the polish on the shoes as it is taken by the same revolving brushes, while they revolve, from beneath the cups, while it flows from the cups. The remainder of the brushes are employed to give the final gloss to the shoes 10 carried by the slowly moving platform.

The machine is run by a motor connected to either end of the main shafts *C, D*. Fig. 2. The brushes will revolve at full speed, while the moving platform by means of the 15 reducing gears, moves very slowly. When anybody is to have a shine, after preliminary cleaning of the shoe by the stationary brushes *H*, the person stands on the platform *I* in the position indicated by the 20 dotted lines *Z*, one foot behind the other: takes hold of the hand railings *O*, and in such position, while the machine is in motion and the platform slowly moving the wire spikes set in the belt or moving platform 25 engage the shoes from beneath, carrying the person slowly along, their shoes passing between the two sets of brushes, from *I* toward *J*, when the person reaches the other end of the machine on the platform 30 *J*, the shining operation is finished.

Of the pulleys *Q, R*, by which means the moving platform slowly revolves the pulley *Q* in the back is set higher than the other *R*, in the front as seen in Fig. 1; in so doing 35 the platform may move easier over the

rollers on an inclined line. The sets of revolving brushes are removable and in the case that black shoes are to be polished after tan, another set of brushes is substituted. For this purpose the bearings *S*, are suitably 40 constructed with removable caps so that the brushes may be changed. The moving platform *E* is a regular leather belt slowly revolving with the pulleys *Q, R*, driven by the reducing gears, sprocket chains, and 45 sprocket wheels *N*. The leather belt is studded to form a rough surface on the upper face of the belt, and by such means the shoe is prevented from slipping off. 50

I claim:

In a shoe shining machine, the combination of a supporting frame, two revolute parallel shafts removably mounted in said frame, a plurality of brushes and blades fixed on each of said shafts, a traveling conveyer belt mounted between the revolving brush shafts, motion transmitting mechanism connecting said revolving shafts and conveyer, a polish dispensing device mounted to discharge polish on one brush 55 on each revolute shaft and having an actuating arm projecting into the path of travel above the conveyer belt and adapted to be actuated by contact with the ankle of a person standing on the conveyer belt. 60

VINCENT RASCHELLA.
